UNITED STATES PATENT OFFICE

130,348

DESIGN FOR A RADIATOR GRILLE FOR AN AUTOMOBILE

Kenneth E. Coppock, Pleasant Ridge, Mich., assignor to General Motors Corporation, Detroit, Mich., a corporation of Delaware

Application March 13, 1941, Serial No. 99,565

Term of patent 7 years

To all whom it may concern:

Be it known that I, Kenneth E. Coppock, a citizen of the United States and a resident of Pleasant Ridge, county of Oakland, and State of Michigan, have invented a new, original, and ornamental Design for a Radiator Grille for an Automobile, of which the following is a specification, reference being made to the accompanying drawings, forming a part thereof.

Figure 1 is a front elevational view of a radia-

tor grille for an automobile showing my new design.

Figures 2 and 4 are sections on the lines 2-2 and 4-4 of Figure 1, Figure 4 being on an enlarged scale.

Figure 3 is a side elevational view of the grille.

I claim:

The ornamental design for a radiator grille for an automobile, as shown.

KENNETH E. COPPOCK.
